(57) **CLAIM**

The ornamental design for an apertured building panel, as
shown and described.

DESCRIPTION

FIG. 1 is a perspective view of a first embodiment of an
apertured building panel;

FIG. 2 is a top view thereof;

FIG. 3 is a bottom view thereof;

FIG. 4 is a front elevation view thereof;

FIG. 5 is a rear elevation view thereof;

FIG. 6 is a right side elevation view thereof; and

FIG. 7 is a left side elevation view thereof.

FIG. 8 is a perspective view of a second embodiment of an
apertured building panel;

FIG. 9 is a top view thereof;

FIG. 10 is a bottom view thereof;

FIG. 11 is a front elevation view thereof;

FIG. 12 is a rear elevation view thereof;

FIG. 13 is a right side elevation view thereof; and

FIG. 14 is a left side elevation view thereof.

FIG. 15 is a perspective view of a third embodiment of an
apertured building panel;

FIG. 16 is a top view thereof;

FIG. 17 is a bottom view thereof;

FIG. 18 is a front elevation view thereof;

FIG. 19 is a rear elevation view thereof;

FIG. 20 is a right side elevation view thereof; and

FIG. 21 is a left side elevation view thereof.

FIG. 22 is a perspective view of a fourth embodiment of an
apertured building panel;

FIG. 23 is a top view thereof;

FIG. 24 is a bottom view thereof;

FIG. 25 is a front elevation view thereof;

FIG. 26 is a rear elevation view thereof;

FIG. 27 is a right side elevation view thereof; and

FIG. 28 is a left side elevation view thereof.

FIG. 29 is a perspective view of a fifth embodiment of an
apertured building panel;

FIG. 30 is a top view thereof;

FIG. 31 is a bottom view thereof;

FIG. 32 is a front elevation view thereof;

FIG. 33 is a rear elevation view thereof;

FIG. 34 is a right side elevation view thereof; and

FIG. 35 is a left side elevation view thereof.
